UNITED STATES PATENT OFFICE

118,455

DESIGN FOR A DISPLAY RACK

Lee A. Shelton and Russel W. Smith, Des Moines,
Iowa, assignors to New Monarch Machine &
Stamping Co., Des Moines, Iowa

Application June 12, 1939, Serial No. 85,456

Term of patent 7 years

To all whom it may concern:

Be it known that we, Lee A. Shelton and Russel W. Smith, citizens of the United States and residents of Des Moines, Polk County, Iowa, have invented a new, original, and ornamental Design for a Display Rack, of which the following is a specification, reference being had to the accompanying drawings, forming a part thereof.

Fig. 1 is a front perspective view of a display rack showing our new design; and

Fig. 2 is a side elevational view thereof.

Fig. 3 is a rear perspective view of the display rack.

We claim:

The ornamental design for a display rack, substantially as shown.

LEE A. SHELTON,
RUSSEL W. SMITH.
